UNITED STATES PATENT OFFICE.

SAMUEL EVANS, OF CHICAGO, ILLINOIS.

WASHING-MACHINE FOR GLASS.

No. 893,063.

Specification of Letters Patent. Patented July 14, 1908.

Application filed August 5, 1907. Serial No. 387,147.

To all whom it may concern:

Be it known that I, SAMUEL EVANS, a subject of the King of Great Britain, and a resident of Chicago, in the county of Cook and State of Illinois, have invented certain new and useful Improvements in Washing-Machines for Glass, of which the following, when taken in connection with the drawings accompanying and forming a part hereof, is a full and complete specification sufficient to enable those skilled in the art to which it pertains to understand, make, and use the same.

This invention relates to a machine for the washing of sheet glass and the object of the invention is to obtain a machine by means of which sheets of glass requiring the use of lye or other fluids injurious to the skin of a person may be washed and cleaned without requiring the operator or operators to come in contact with such lye or other liquid or to handle such glass while the lye or other liquid is thereon.

A further object of the invention is to obtain means whereby sheets of glass of varying size and thickness may be thoroughly washed with but little breakage thereto.

A further object of the invention is to obtain a machine whereby the washing of sheets of glass is continuous; and a machine which may be economically operated by two persons, one to place the sheets of glass which are to be washed in or on the machine, and one to take the washed sheets of glass from the machine.

In the drawings referred to Figure 1 is an elevation of a washing machine embodying this invention, with portions of the side of the frame thereof broken away to expose operative parts of the machine to view. Fig. 2 is a top plan view of a machine embodying this invention. Fig. 3 is a vertical section of a machine embodying this invention on line 3—3 of Fig. 1 viewed in the direction indicated by the arrows. Fig. 4 is a vertical section of a machine embodying this invention on line 4—4 of Fig. 1, viewed in the direction indicated by the arrows. Fig. 5 is a vertical section of a machine embodying this invention on line 5—5 of Fig. 1, viewed in the direction indicated by the arrows. Fig. 6 is a vertical section of a machine embodying this invention on line 6—6 of Fig. 1, viewed in the direction indicated by the arrows. Fig. 7 is a vertical section of a machine embody-

ing this invention on line 7—7 of Fig. 1, viewed in the direction indicated by the arrows.

A reference letter applied to designate a given part is used to indicate such part throughout the several figures of the drawings wherever the same appears.

A is the frame of the machine, and B is an apron comprising flexible belts b , b , and slats b' , b' . C, Figs. 1, 2 and 7, is a shaft rotatably mounted on frame A and C' Figs. 1, 2 and 5 is a shaft similar to shaft C which is also rotatably mounted on frame A. D, D' are, respectively, wheels on shafts C and C'. Flexible belts b , b , of apron B extend over the wheels D, D', respectively, and such apron is actuated by the rotation of the shaft C', the wheels D' being rigidly secured to such shaft.

E is an inclined table supported by the frame A, see Figs. 1 and 6. It will be observed that the lower end of inclined table E is not adjacent to the shaft C but is placed at such a distance therefrom that when a sheet of glass to be washed is placed on the apron B the lower end of such sheet of glass will be moved by the apron to over the collecting pan F by the time the upper end or edge of such sheet of glass is over such inclined table. When the upper end or edge of a sheet of glass on the apron B is over the inclined table E liquid is directed onto such sheet of glass by or from such inclined table, the apron resting on or near to such inclined table so that liquid delivered from receptacle G on to the apron flows down the inclined table, and sufficient liquid is, in the operation of the machine, discharged from the receptacle G to have at all times enough thereof on inclined table E to wholly immerse such apron and any sheet of glass which is on the apron over the inclined table.

H, H', are tanks into one or both of which liquid from collecting pan F is discharged.

f is a steam supply pipe branched at the lower end thereof to discharge into the tanks H, H', and f', f'', are valves in pipe f to control the discharge of steam therefrom. The liquid contents of tanks H, H', respectively are heated by discharging steam thereinto from such pipe f.

h is a water supply pipe arranged to discharge into tank H'.

I is a pipe one end whereof is T-shaped and

in communication with the tanks H, H', respectively, and the other end whereof is in communication with receptacle G.

i, i, are valves in pipe I.

5 I' is a pump interposed in pipe I by means of which liquid in tanks H, or H', as preferred, is forced through such pipe I and delivered into receptacle G.

This machine is, as heretofore stated, designed to be used for the cleaning of glass requiring strong lye or other chemical compounds and I have found that where lye is used provision should be made for prevention of foaming, that is, to prevent the formation of air bubbles; and for this purpose I provide the auxiliary receptacle g, having the foraminated bottom g' (see Fig. 1) into which auxiliary receptacle and through the foraminated bottom thereof liquid from tank 20 G flows onto the apron B and inclined table E adjacent to the upper end of such inclined table.

By means of the two tanks H, H', respectively provided with steam pipes f, f, 25 warmed lye, (as say in tank H') or warmed water, or water saturated with any desired chemical, (as say in tank H), may be used over and over in the cleaning of glass and maintained at a determined temperature. I 30 prefer to construct the tanks H, H', of sufficient size so that not less than one half a day's run may be made before the cleaning liquid contained in either one of such tanks becomes so dirty as to require a fresh supply.

35 J, J, Figs. 1 and 2, are adjustable brushes adjacent to the apron B, and j, j, are set screws by means of which such brushes are adjusted. These brushes J, J, are so near to the apron B that when the sheets of glass 40 on such apron are carried thereunder such brushes are in contact therewith, but do not rest thereon with sufficient force to break the glass.

K is a roller the surface whereof is preferably felt or other like material, rotatably mounted on frame A to come in contact with a sheet of glass on the upper surface of such sheet at the time the glass is about to be delivered from apron B onto apron L. This 50 roller K has two functions; first, to insure the forward movement and delivery of the sheet of glass onto apron L, and secondly, to prevent the carrying over of any considerable quantity of liquid in case brushes J, J, should leave such liquid on the glass. Apron L is constructed in substantially the same manner as apron B, that is, with flexible belts l, l, and cross slats l' and the belts l pass over or around wheels M, M', on shafts 55 m, m', respectively.

N is a driving wheel on shaft m by means of which such shaft is rotated and apron L actuated. A receiving and a delivering apron (b and L) with an open space between them

are used so that the several operative mechanisms arranged in combination therewith (which are about to be described), may thoroughly rinse the sheet of glass and remove therefrom the liquid by means of which it has been washed while on apron B.

65 O, O', are rollers one above the other below the plane in which the sheet of glass which is being transferred onto apron L moves. These rollers move in the same direction; the periphery of roller O' at the 70 point where the sheet of glass rests thereon moving in the same direction in which the sheet of glass is moving and the periphery of roller O at the point thereof in contact with such sheet of glass moving in the direction 75 opposite to the movement of such sheet of glass. I have made the roller O, O', with brushes on the periphery thereof; that is, such rollers form brush rollers.

O'', O'', are the shafts of the respective 80 brush rollers O, O', and are rotatably mounted in frame A.

P, P', are, respectively, water pipes extending transversely across the machine from one side thereof to the other and provided with perforations directing the water from such pipes on to the upper and lower faces of a sheet of glass which is being transferred from apron B to apron L before such sheet of glass is delivered to such apron L. Transverse pipe P is above and transverse pipe P' is below the plane of the sheet of glass.

Q is a collecting pan under the apron L by means of which the water used to rinse the glass on apron L is collected, and discharged, 100 so far as this machine is concerned, to waste.

R, R', are motors. Motor R actuates aprons B and L, respectively, and roller brushes O, O'; by means of the several shafts S, S', S'', intermeshing gears S', S'', pulleys 105 T, T', t, t', and belts U, U', U'', U''.

u is a belt passing over the driving pulley of motor R' and the driven pulley of rotary pump I'.

The operation of this machine is as follows:—A sheet of glass is laid on the apron at the lower end thereof with the side of the glass particularly to be cleaned up. The apron slowly conveys the sheet of glass forward and upward and when the forward edge 115 of such sheet of glass comes over the inclined table the liquid flowing down such table will flow over the sheet of glass, on both the under and upper faces thereof. Where the sheets of glass to be cleaned have previously 120 been put through the sand blast process and have thereon, adhering thereto, pieces of glue I find that a washing liquid consisting of a strong solution of lye at a temperature of from say one hundred and ten degrees Fahrenheit to (where a single thickness of glass is to be cleaned) say one hundred and fifty degrees Fahrenheit gives good results.

Where lye or other liquid liable to froth or bubble is used the supplemental pan with a foraminated bottom is used, and the liquid flowing thereinto from receptacle G flows out 5 therefrom through the holes in such bottom. As the apron travels slowly the sheet of glass is subjected to the flow of cleaning liquid say from two to five minutes, as desired. As the sheet of glass passes under the brushes J, J, 10 the cleaning liquid on the top surface is brushed therefrom and the glass is then transferred to apron L, in the course of such transfer passing between the brush rollers O, O'. The cleaning liquid falling from the inclined table under apron B flows into the collecting pan F and from thence into the one 15 of the tanks H, H', which is in use. Such liquid is maintained at the determined temperature by injecting thereinto steam from pipe f,—the valve f' being opened sufficiently 20 to obtain and maintain the determined temperature in such cleaning liquid.

The transverse pipes P, P', are perforated so that when no sheet of glass is passing between the brush rollers many small jets of 25 water are thrown towards such rollers and when a sheet of glass is passing between such brush rollers these small jets of water are directed from above down onto the upper surface 30 of such sheet of glass and from below up onto the under surface thereof. The water thus thrown on to the sheet of glass from these jets is preferably cool, say about seventy degrees temperature, and I have 35 used water direct from the city pressure pipes. The water from the glass drops into the collecting pan and flows to waste.

Having thus described my invention and the operation thereof what I claim is new 40 and desire to secure by Letters Patent is,—

1. In a machine for cleaning glass, a frame, an inclined receiving apron mounted in one end of the frame and a delivery apron mounted in the other end of the frame, an 45 inclined table over which the receiving apron is moved for a portion of the length of such apron, a collecting pan underneath the inclined table and underneath the apron, a tank under the collecting pan, such tank 50 arranged to receive liquid discharged from the collecting pan, a liquid receptacle above the receiving table, means to transfer the liquid in the tank to the receptacle above the table and to discharge such liquid onto the apron and inclined table, means to 55 transfer a sheet of glass from the receiving apron to the delivery apron, and means to discharge liquid on the upper and under 60 faces of a sheet of glass while such glass is being transferred from the receiving to the delivery apron; substantially as described.

2. In a machine for cleaning glass, a frame, an inclined receiving apron mounted in one 65 end of the frame and a delivery apron

mounted in the other end of the frame, an inclined table over which the receiving apron is moved for a portion of the length of such apron, a collecting pan underneath the inclined table and underneath the apron, 70 a tank under the collecting pan, such tank arranged to receive liquid discharged from the collecting pan, a liquid receptacle above the receiving table, means to transfer the liquid in the tank to the receptacle above 75 the table and to discharge such liquid onto the apron and inclined table, rollers at the upper end of the receiving apron, such rollers arranged to come in contact with a sheet of glass on the receiving apron and to transfer 80 such glass from the receiving to the delivery apron, and means to discharge liquid onto the sheet of glass while such glass is being transferred; substantially as described.

3. In a machine for cleaning glass, a frame, 85 an inclined receiving apron mounted in one end of the frame and a delivery apron mounted in the other end of the frame, an inclined table over which the receiving apron is moved for a portion of the length 90 of such apron, a collecting pan underneath the inclined table and underneath the apron, a tank under the collecting pan, such tank arranged to receive liquid discharged from the collecting pan, a liquid receptacle above 95 the receiving table, means to transfer the liquid in the tank to the receptacle above the table, and to discharge such liquid onto the apron and inclined table, an additional receptacle provided with a foraminated bottom, such additional receptacle arranged to receive liquid discharged from the first 100 named receptacle and to discharge such liquid through such foraminated bottom on to the apron and inclined table, means to transfer a sheet of glass from the receiving 105 apron to the delivery apron, and means to discharge liquid on the upper and under faces of a sheet of glass while such glass is being transferred from the receiving to the delivery apron; substantially as described.

4. In a machine for cleaning glass, a frame, an inclined receiving apron mounted in one end of the frame and a delivery apron mounted in the other end of the frame, an 115 inclined table over which the receiving apron is moved for a portion of the length of such apron, a collecting pan underneath the inclined table and underneath the apron, a tank under the collecting pan, such tank 120 arranged to receive liquid discharged from the collecting pan, a liquid receptacle above the receiving table, means to transfer the liquid in the tank to the receptacle above the table and to discharge such liquid onto 125 the apron and inclined table, an additional receptacle provided with a foraminated bottom, such additional receptacle arranged to receive liquid discharged from the first named receptacle and to discharge such 130

liquid through such foraminated bottom onto the apron and inclined table, rollers at the upper end of the receiving apron, such rollers arranged to come in contact with a sheet of glass on the receiving apron and to transfer such glass from the receiving to the delivery apron, and means to discharge

liquid onto the sheet of glass while such glass is being transferred; substantially as described.

SAMUEL EVANS.

In the presence of—

CHARLES TURNER BROWN,
CORA A. ADAMS.
